BELT BUCKLE FRAME

Sol Bartner, New York, N. Y.

Application February 2, 1949, Serial No. 638

Term of patent 3½ years

(Cl. D17—1)

To all whom it may concern:

Be it known that I, Sol Bartner, a citizen of the United States of America and a resident of the city of New York, county of Queens, and State of New York, have invented a new, original, and ornamental Design for a Belt Buckle Frame, of which the following is a specification, reference being had to the accompanying drawing, forming a part hereof.

In the drawing:

Fig. 1 is a plan view of a belt buckle frame, showing my new design;

Fig. 2 is a section thereof taken on line 2—2 of Fig. 1; and

Fig. 3 is a side edge view of the disclosure in Fig. 1.

I claim:

The ornamental design for a belt buckle frame, substantially as shown.

SOL BARTNER.
